UNITED STATES PATENT OFFICE.

HUGO J. BAUR, OF CHICAGO, ILLINOIS, ASSIGNOR TO JOHNSON COIN COUNTING MACHINE COMPANY, A CORPORATION OF NEW YORK.

COIN-COUNTING MACHINE.

1,382,050.

Specification of Letters Patent. Patented June 21, 1921.

Application filed June 25, 1919. Serial No. 306,606.

To all whom it may concern:

Be it known that I, Hugo J. Baur, a citizen of the United States, and a resident of the city of Chicago, in the county of Cook and State of Illinois, have invented certain new and useful Improvements in Coin-Counting Machines; and I do hereby declare that the following is a full, clear, and exact description of the same, reference being had to the accompanying drawings, and to the numerals of reference marked thereon, which form a part of this specification.

My invention has reference more particularly to a coin counting machine which is adapted to register the number of coins passed through the machine and is also adapted to separate and count various predetermined numbers of coins from a mass of coins.

It is an object of my invention to provide a device of this character in a simple, compact and portable form for counting coins.

Another object of my invention is to provide a coin counting machine of this character which may be readily adjusted to count coins of various sizes.

A further object of my invention is to provide a coin counting device which may be set to count out certain predetermined numbers of coins of any desired denomination.

Another object of my invention is to provide a coin counting device which may be set to count out certain predetermined numbers of coins and having resetting means for beginning the count anew and provided with locking means to prevent passage of coins through the device during the resetting operation.

Another object of my invention is to provide a coin counting device having a rotary coin carrier for transferring the coins by centrifugal force to the counting position.

My invention also has other important objects which will appear from the following specification and the accompanying drawings, in which I have described and illustrated my invention in a preferred form.

On the drawings:

Figure 1 is a top view of the coin counting device.

Fig. 2 is a side view thereof.

Fig. 3 is a sectional view on the line 3—3 of Fig. 1, with parts in elevation and parts omitted.

Fig. 4 is a sectional view on the line 4—4 of Fig. 3.

Fig. 5 is an enlarged fragmentary sectional view illustrating particularly the mechanism for adjusting the device according to the thickness of the coins, said view being taken on the line 5—5 of Fig. 4.

Fig. 6 is a sectional view on the line 6—6 of Fig. 5.

Fig. 7 is a diametrical sectional view of the coin carrier.

Fig. 8 is a fragmentary sectional view of the casing showing the manner of supporting and operating the upper coin distributing disk or ring.

Fig. 9 is an enlarged fragmentary view of a roller support.

Fig. 10 is a fragmentary view of the under side of the coin distributing disk showing the coin pushing lever.

Fig. 11 is an enlarged sectional view on the line 11—11 of Fig. 10.

Fig. 12 is an enlarged fragmentary view of the coin counting mechanism shown in Fig. 4, with the upper plate of the frame thereof removed.

Fig. 13 is a sectional view substantially on the line 13—13 of Fig. 12, with the counting mechanism beyond this line shown partly in section.

Fig. 14 is a sectional view on the line 14—14 of Fig. 13.

Fig. 15 is a view partly in section and partly in elevation of the mechanism for regulating the number of coins to be counted at a time.

Fig. 16 is a sectional view of the oscillating frame for regulating the number of coins to be counted at a time, and the adjusting pin therefor.

Fig. 17 is a view partly in section of the mechanisms for adjusting the gears to change the count.

Fig. 18 is an enlarged detail sectional view of the gearing for changing the count.

Fig. 19 is a sectional view on the line 19—19 of Fig. 18.

Fig. 20 is a sectional view on the line 20—20 of Fig. 18.

Fig. 21 is an enlarged fragmentary side view of the star counting wheel and mecha-

nism for locking the star wheel from rotation.

Fig. 22 is a detail view of the star wheel and locking mechanism.

5 Fig. 23 is an enlarged fragmentary detail view of auxiliary locking mechanism for preventing passage of coins through the machine except at the proper time.

As shown on the drawings:

10 The reference numeral 1 indicates the casing of the machine, which is provided with a large circular opening in the top surrounded by an enlarged rim 2, with a groove 3, in the lower face to afford a ball race for ball bearings. A hopper 4, is secured to the rim 2, to direct the coins through the opening in the top of the casing into the machine, and may have the coins supplied thereto through a spout or chute 5, or in any other 15 convenient manner. The lower end of the casing 1, is expanded or otherwise constructed to afford a shoulder against which a bottom plate 6, is secured by means of the cap screw 7, (Fig. 8) which are threaded 20 into internal bosses on the inner face of the casing.

The casing 1 and bottom plate 6 are both substantially circular and extend outwardly at one side to afford a lateral compartment 30 for the counting mechanism, which compartment has an opening at the top closed by a plate 8, which is secured to the casing 1 in any convenient manner. A bracket 9 is secured to the bottom plate 6, and supports an upright shaft 10, at the center of the circular portion of the casing 1 and bottom plate 6, said bracket being arched at 11, to afford an upper bearing for the shaft, in which the latter is adapted to rotate freely and reciprocate to a limited extent. Mounted at the 40 upper end of the shaft 10, is a disk 12, which is of larger diameter than the opening through the upper wall of the casing 1, and has the edge bent downwardly as shown at 45 13, and is provided with a central reinforcing plate 14 therunder, which, together with the disk 12, is secured on the reduced upper end of the shaft 10, against the annular flange 15 of this shaft by means of the nut 16, which is threaded onto the upper end of the shaft. A flat ring 17, with an upturned flange 18, around the opening forming a raceway for ball bearings is mounted above the disk 12, so that the bearings 19 engage 50 the ball race 3, of the rim 2, of the opening in the top of the casing to permit the ring 17 to rotate about the opening, and the lower end of the hopper 4 projects inside the flange 18, to readily discharge the coin onto the 55 upper surface of the disk 12. A reinforcing ring 200 is secured to the under side of the ring 17, around the opening therethrough, and the outer edge of the ring 17 is bent upwardly and outwardly at 20, to afford a flange corresponding to and reversely ar-

ranged with reference to the flange 13, of the plate 12. A ring 21, having an opening therethrough of substantially the size of the flat portion of the plate 12, is mounted concentric with and between the plates 12 and 17, being supported by a plurality of beveled rollers 22, (see Figs. 4 and 8) which are journaled on the plate springs 23 and 24, and engage the inclined flanges 13 and 20, of the disk 12 and ring 17, respectively. The 75 disk 12, is adjustable vertically as herein-after more fully explained, and this manner of supporting the ring 21, permits such adjustment, as the tension of the springs 23 and 24 enables the rollers 22 to move upon 80 the inclined flanges 13 and 20, and maintain constant engagement therewith, and the ring 21 is thereby maintained in proper position between the plates 12 and 17. The plate 12 is adapted to rotate with the shaft 10, and as 85 the upper plate or ring 17 is also mounted to rotate on the ball-bearing 19, the engagement of the rollers 22, with the flanges 13 and 20, of these plates, imparts rotation to the ring 17, in a direction reverse to that 90 of the plate 12. The ends of the springs 23 and one end of each of the springs 24 are bent inwardly and slotted at 25, as shown in Fig. 9, to straddle the plate 21, to sustain the plate at the proper elevation, and the 95 ends of these slots 25 engage at the ends of the notches 26, in which the rollers 22 are located so as to lock the spring against circumferential movement relatively to the plate, and the ends of the springs 23 and 100 one end of each spring 24 are sprung against the wall of the casing 1, to afford a tension not only to maintain the rollers 22, in engagement with the inclined flanges 13 and 20, but also to afford frictional engagement 105 with the wall of the casing to prevent rotational displacement of the ring 21. One end of each of the springs 24, extends beyond the circular wall portion of the casing 1, into the compartment which contains the 110 counting mechanism, and is connected with a radially projecting portion of the plate 21, (see Fig. 4) in a suitable manner so as to maintain the springs at a tension with the roller properly engaging the flanges 13 and 115 20, the opposite end contacting with the wall of the casing 1.

For regulating the elevation of the plate 12, and the shaft 10, there is a frame 27, (Figs. 3, 5 and 6) pivoted to the bracket 9, 120 at 28, and pivotally hung in the frame 27 is a support having a socket 29, (see Fig. 3) affording a bearing in which the lower end of the shaft 10 is engaged. This socket or bearing 29, fits in a depression 30, formed in 125 the bottom wall 6, of the casing of the device, to hold the socket 29 in the upright position. A bar 31, which is formed with a quarter turn bend intermediate of its ends to afford a horizontal face at the outer end 130

and a vertical face at the inner end, extends inwardly from the compartment which contains the counting mechanism and has the inner end engaged between the free end of the frame 27, and a guide plate 32, secured to the bottom plate 6. This plate 32 is provided with a lip 33, along the upper edge overlying the upper edge of the vertical portion of the bar 31, to permit the bar 31 to move only in a longitudinal direction, and the inner end of the bar has a longitudinal slot 40 comprising stepped portions 34, 35, 36 and 37, adapted to be engaged by a pin 38, on the outer end of the frame 27, which pin projects through this slot and into a vertical slot 39 (Fig. 3) in the guide plate 32, which latter slot prevents lateral displacement of the pin 38 and frame 27, and permits the vertical adjustment of the pin 20 which is effected by the step arrangement of the slot 40 in the bar 31. Thus it will be noted that by adjusting the bar 31, longitudinally the various stepped portions of the slot 40, come into engagement with the pin 38, and raise or lower the latter together with the frame 27, with which it is connected, and thereby raise and lower the shaft 10 and plate 12, carried thereby. The steps 34, 35, 36 and 37 are arranged to elevate the plate 12 to afford the proper distance between the plate 12 and the ring 17, to afford the proper distance therebetween to correspond to the thickness of the coins to be counted, as, for example, for pennies, dimes, nickels and quarters respectively, as in the present construction. For adjusting the bar 31 to bring the desired step of the slot 40, in engagement with the pin 38, there is a vertical shaft 41, which extends down through the side chamber of the casing 1, and is journaled in a frame 42, secured in the side chamber, said frame being provided with a bearing 43, at the base thereof and a bracket 44, with a bearing 45, for this shaft. The upper end of this shaft projects through the top of the casing 1, and the cover plate 8, and has a lever 46, secured to the upper end, and provided with an operating knob 47, having a latch pin or plunger 48, to engage with the perforations 49, (Fig. 1) in the cover plate 8, for locking the crank 46 in definite positions of adjustment. The shaft 41 projects through a slot 50, in the outer end of the bar 31, and has a crank 51, secured thereon directly above the outer end of the bar 31, so as to confine the outer end of the bar between the hub of the crank and the bearing 43, and the crank pin 52, of this crank engages a transverse notch 53, in the bar 31, so that when the shaft 41 is rotated the bar 31 is projected longitudinally thereby. The perforations 49 in the cover plate 8 are arranged so that when the crank or handle 46 is adjusted to engage with any 65 of the perforations the corresponding

stepped portion of the slot 40 engages the pin 38.

In the operation of the device the coins are impelled to the periphery of the plate 12, by centrifugal force and are held at this point by engagement with the ring 21, and the reinforcing plate 14, on the underside of the plate 12, is provided with one or more levers 54, (Figs. 7, 10 and 11) pivotally mounted thereon at 55, and actuated by a spring 56, so that a short finger 57, at the outer end of the lever is normally held up through a perforation 58, provided therefor adjacent the outer edge of the plate so as to engage the coins and carry them to the counting and discharging position.

Pivoted at 60, (Figs. 4 and 12) on a lateral extension 59, of the frame 42, is a finger 61, of curved form as shown, the free end of which projects between the plate 12 and ring 17, (Fig. 5) and is adapted to hold the coin up against the counting mechanism as it is moved thereby, and after passing the counting position to direct the coin outwardly from the plate 12, so that it will fall into a chute 62, which inclines outwardly and downwardly from the outer edge of the plate 12, through the wall of the casing 1, to discharge the counted coins to the exterior thereof.

A shaft 63 (Figs. 4, 12, 13 and 15) is journaled vertically in the frame 42, in the side compartment of the casing, and has a ten-toothed star wheel 64, secured thereon so that the periphery thereof projects between the plates 12 and 17 sufficiently to be engaged by a coin carried thereby when the finger 61 is properly adjusted for a coin of that size, and there is a register 65, of any suitable type, inclosed in a casing 67, into which the upper end of the shaft 63 projects. This shaft is there provided with a beveled gear 68 meshing with a bevel gear 69, on the register operating shaft or otherwise connected therewith so that the movement of the star wheel 64, a distance of one tooth operates the register one step. The register is not shown in detail as there are a great many types of such mechanism which are well known and the particular construction thereof forms no part of my invention. The register as usual has a series of dials or cylinders which are to be viewed at a certain place to indicate the count and has a resetting knob 66, and the casing 67 is provided with an opening 70, through which the numbers designating the count are visible.

From the foregoing it is apparent that the finger 61, is required to be adjusted to correspond to the diameter of the particular coin to be counted, and in order to conveniently effect such adjustment the shaft 41, which regulates the vertical adjustment of the plate 12 to correspond with the thickness

95

100

105

110

115

120

125

130

of the coin, has a cam 71, (Fig. 12) which engages a slot 72, in the lever or finger 61, and is arranged so that as the shaft 41 is operated by the crank 46, to regulate the vertical adjustment of the plate 12 to correspond to the thickness of the coin to be counted, the lever or finger 61, is simultaneously adjusted thereby to afford a space between the free end of the finger 61 and the star wheel 64, corresponding to the diameter of the coin to be counted, which is sufficient to cause the coin to pass in proper contact with the star wheel 64 to operate same so as to advance the register one step.

15 The finger 61, is positioned close to the upper face of the plate 12, sufficient separation being permitted so that the necessary adjustment of the plate 12 in accordance with the thickness of the coin is possible, and as the finger 57, at the outer end of the lever 54, which forces the coin past the counting position projects above the surface of the plate 12, it is necessary that the finger should be retracted sufficiently to pass under the lever or finger 61. For this purpose a roller 73, (Figs. 7 and 10) is mounted at the side of the upper bearing of the shaft 10, in position to engage and raise the inner end of the lever 54, at the time the finger 57 is about to contact with the lever or finger 61, and thereby depresses the finger 57, and permits same to pass under the lever or finger 61, after which it is returned by the tension of the spring 56 to the normal position.

This device is adapted to count out certain predetermined numbers of coins for which the device may be set, and after such predetermined number has been counted out to interrupt further operation of the machine, and for this purpose I have provided the following mechanism. Loosely mounted on the shaft 63, below the star wheel 64, is a sleeve 74, (Figs. 11 and 15) with a screw thread 75 extending lengthwise thereof, terminating at the lower end in a groove 76, and this sleeve 74, has a gear wheel 75^a secured thereto at its lower end. A corresponding gear wheel 76, (Figs. 15 and 18) is secured on the shaft 63, at a distance from the gear wheel 75, and between these gear wheels there is also mounted on the shaft 63, a disk 77, having a single notch 78, (Fig. 20) and a plate 79, secured to the underside of the disk with a tooth 80, at each side of the notch. Secured to and extending up from the bottom plate 81, of the frame 42, parallel with the shaft 63, is a spindle 82, having a combination pinion member slidably mounted thereon. This combination pinion member comprises the upper pinion 83, (Figs. 17 and 18) having a wide face so as to remain in mesh with the gear wheel 75^a in the several positions of adjustment for which the combination pinion member is adapted, and this member has a mutilates pinion 84, adjacent the lower end, which, when the combination pinion member is in the lowermost position, meshes with the gear wheel 76, on the shaft 63. Thus gear 84 is driven by shaft 63; gear 83 which is connected to gear 84 will revolve and operate gear 76 and sleeve 74 at the same rate of speed as the gear wheel 76. The upper ends of alternate teeth of the pinion 84, beyond the point of engagement with the gear 76, are cut away so that they are of shorter length than the adjoining teeth, and when the combination pinion member is elevated to the upper position, the pinion 84 is disengaged from the gear wheel 76, and all the teeth thereof are in position to be engaged by the teeth 80, of the plate 79, whereas the long teeth only are positioned to engage the periphery of the disk 77, thus affording a Geneva gear connection between the shaft 63 and the gear wheel 75^a, with which the pinion 83 remains in mesh at such time, to rotate the gear 75^a one-tenth of a revolution with every revolution of the shaft 63 and disk 77. For gears 83 and 84 make $\frac{1}{10}$ revolutions for one rotation of gear 76 or shaft 63 when said gear 76 directly drives the gear 84. But when gears 83 and 84 are driven by disk 77 with plate 79 having the two teeth 80, the said gears 83 and 84 will rotate only once for every three rotations of shaft 63 or $\frac{1}{3}$ for every revolution of shaft 63, since the gear 84 is advanced two teeth for every revolution of the disk 77. This produces a ratio of 10 to 1. It should be here noted that as disk 77 revolves, when the gear 84 has been raised, the outer edge of a tooth 80 will strike a short tooth thereof and advance it one step thereby rotating gear 84 and bringing a long tooth into the notches of the disk and plate 79. Further rotation will now carry the long tooth one step, the next short tooth passing under the plate 77, for which purpose it has been reduced, and remaining in position to be engaged by the outer edge of a tooth 80 in the next revolution. A yoke 87, embraces the combination pinion member 83—84, and the arms thereof slidably engage the spindle 82, so as to serve for adjusting the combination pinion member lengthwise of the spindle 82, and there is another yoke 88, secured to the yoke 87, having the arms thereof provided with square perforations engaging a square shaft 89, (Figs. 13, 18, 19 and 20) extending upwardly from the bottom plate 81, of the frame 42, parallel with the spindle 82, so as to serve, together with the spindle 82, as a guide for the vertical adjustment of the double yoke member. A shaft 90, (Figs. 6 and 17) extends through the wall of the casing 1, and the upright portion of the frame 2, and has a knob 91, on the outer end whereby it may be rotated, and at the inner end has an 130

eccentrically arranged pin 92, engaged between a pair of laterally extending projections 93 on the yoke 87, so that rotation of the knob 91 and shaft 90, slides the combined 5 yoke member 87-88, on the spindle 82 and square shaft 89, and with it the combination pinion member 83-84, so as to afford either a one-to-one drive from the gear wheel 76 to the gear wheel 75^a, or a ten-to-one drive from 10 the Geneva gear plate 77 to the gear wheel 75^a. The knob 91 may be provided with a pointer 93^a, (see Fig. 14), to indicate the proper adjustment to effect the required meshing of the combination pinion member 15 with the gears, or a stop may be provided to limit the operation of the knob at each extremity of its adjustment, or any convenient means provided to enable the operator to know when the desired adjustment is 20 effected.

A stud 94, (Figs. 13, 14 and 15), projects inwardly from the upright portion of the frame 42, and has a lever 95, pivoted thereon with the upper end projecting through a slot 25 in the top wall of the side compartment of the casing and in the cover plate 8, to permit a limited oscillation of the lever. An arm 96, is pivoted on this lever 95, and has a wide face at the outer end positioned so the 30 edge thereof engages the thread 75, of the sleeve 74, and other mechanism to be hereafter described, and there is a light spring 97, on the pivot pin 98, of the arm 96, for elevating the outer end of the arm, and also 35 a spring 99, on the pivot stud 94, of the lever 95, which holds the lever 95 at a tension to engage the outer end of the arm 96, with the thread 75, of the sleeve 74.

An adjustable frame comprising the 40 spaced plates 100 and 101, (Figs. 5, 6 and 16) which are secured together by the pins 102, to operate as a unit, is pivotally mounted on a stud 103, extending inwardly from the upright portion of the frame 42. The 45 plate 100 is arranged adjacent the sleeve 74, and is adjustable to and from the outer end of the arm 96, and the edge of this plate 100, against which the end of the arm 96 is adapted to engage, is of irregular formation (see 50 Fig. 15) so as to determine the place along the threaded portion 75 of the sleeve 74, at which the outer end of the arm 96, may be engaged therewith. As hereinbefore stated, the sleeve 74, immediately below the threaded portion 75 thereof, is grooved at 76^a, this construction being provided so that when the thread 75, which is pitched so that the operation thereof by the passage of coin through the machine forces the outer end of 60 the arm 96 downwardly, will enable the arm 96, to be forced inwardly into the groove 76^a, by the spring 99, as the end of the arm reaches the lower end of the screw thread 75, and by such movement engages trip mechanism to be hereinafter described for arrest-

ing the operation of the mechanism and prevent coins passing through the machine. A corresponding notch 104, is provided in the plate 100, so that in the extreme position of adjustment of the plate 100, the latter does 70 not interfere with the inward throw of the arm 96. This plate 100, has the edge thereof adjacent the outer end of the arm 96, divided into angularly arranged portions 105, 106, 107, 108 and 109, which are so positioned 75 with reference to the thread 75, of the sleeve 74, that when the plate 100 is adjusted to prevent engagement of the outer end of the arm 96, with the thread 75, except at the lower end of a certain one of the angular portions of 80 the edge, the angular portions of the edge of the plate above this point are so related to the outer end of the arm 96, as to direct same downwardly therealong until the outer end of the arm engages the thread at the lower 85 end of the particular angular portion of the edge, and the operation of the sleeve 74, which is required thereafter to move the outer end of the arm 96 downwardly to release from the thread and engage the notch 90 76, requires the passage of a predetermined number of coins past the star wheel 64 and thus enables a definite predetermined number of the coins to be counted, whereupon the operation of the machine is arrested. For 95 example, in Fig. 15, the plate 100 is shown in position of adjustment so that the outer end of the arm 96, engages the thread 75, at the lower end of the angular portion 107, of the plate, and when so engaged, operation 100 of the sleeve 74, effected by the carrying of forty coins past the star wheel 64 is required to move the end of the arm 96 down into engagement with the groove 76, at which time further operation of the machine is arrested. 105 When the plate 100, is set at this position, the angular portions 107, 108, and 109, are arranged so that the arm 96, when withdrawn from engagement with the sleeve 74, by the operation of the lever 95, and thrown upward by the tension of its spring 97, comes into engagement with some portion of these latter mentioned angular portions, and when the lever 95 is released and returned toward the normal position by its spring 110 99, the outer end of the arm 96 slides downwardly along the angular edges 107, 108 and 109 and comes to rest at the lower end of angular portion 107 in engagement with the thread on the sleeve 74. By adjusting the 115 plate 100, on its pivot 103, the arm 96, may be arranged to engage the threads 75 at the lower end of any one of the angular portions 105, 106, 107, 108 and 109, and effects an adjustment to count 20, 25, 40, 50 or 100 120 coins respectively, or any other number of coins which the machine may be designed to count. The plate 101 moves with the plate 100, and is adapted to locate and hold the plate 100 in the proper position to effect the 130

desired count, and to this end is provided with notches 112, (see Fig. 13) at the free end, with which a pawl 113, engages, said pawl being pivotally mounted on a stud 114, 5 on the inner face of the upright portion of the frame 42, and resiliently held in engagement with the notches 112, by a spring 115, (Fig. 6) which is coiled about the pivot 114, and engages over the pawl 113. These 10 notches 112, are arranged so that when the pawl is engaged therewith the plate 100 is adjusted and held at the proper position to engage the arm 96, with the screw thread 75, to effect a predetermined count for which the 15 machine is adapted. A pin 116, is secured in a socket 118, (Figs. 14 and 16) in the plate 100, and projects through an arcuate slot 117, (Fig. 2) in the wall of the casing 1, and a corresponding slot in the upper portion 20 of the frame 42, and has a knob 119, on the outer end so that the frame 100—101, may be adjusted to the desired position from the exterior of the casing. There is a pointer 120 on the knob 119, which moves across a 25 graduated scale 121, at one side of the slot 117, the scale being marked to correspond with the various adjustments of the frame 100—101, to indicate the number of coins counted by the device when the frame is 30 adjusted to such a position.

The star wheel 64, which is engaged and rotated by the coins, as the latter pass through the machine, is engaged by a roller 122, (Fig. 12) mounted on a swinging arm 123, which is pivoted on an upright stud 124, and held resiliently in contact with the star wheel by the spring 125, to prevent accidental operation of the star wheel and overthrow thereof, and to hold the star 40 wheel in proper position to be engaged by each succeeding coin. The stud 124, extends between the upper horizontal plate of the frame 42 (see Fig. 5) and the lateral extension 59, thereof and has a lever 126, (see Fig. 22) loosely pivoted thereon having an end extending so that it may be swung to and from engagement with notches 127, of a cam plate 128, which is secured to the under side of the star wheel 64. This lever 50 126, is designed to engage and interrupt further operation of the star wheel when the predetermined number for which the machine has been set has been registered by the passing coins, and as the numbers 55 which are adapted to be counted are multiples of five and the star wheel requires the passing of ten coins to complete a revolution, there are two of such notches 127, arranged to arrest further operation of the 60 device upon a predetermined multiple of five being registered on the registering mechanism. This lever 126, is free to rotate on its pivotal axis except for a limited amount of frictional engagement which is provided 65 to prevent accidental displacement of the

lever from any position which it may occupy, and there is a notch 129, in this lever at one side of the pivot 124, through which the lever 95 extends, (Figs. 12 and 13) and abutments 130 and 131, at opposite ends of the 70 notch which are arranged to be engaged by the lever 95, to control the operation of the lever 126. When the lever 95, is thrown to the right so as to engage the abutment 131 (see Fig. 12) the opposite end of the lever 75 126 is thrown free of engagement with the cam wheel 128, and remains so until the lever 95 moves to the left sufficiently to engage the abutment 130, whereupon the lever 126 is shifted so as to engage one of the 80 notches 127 of the cam wheel 128.

An additional locking device is provided consisting of a member 132, (see Fig. 23) which is mounted on a bracket plate 133, which latter is secured to the vertical portion of the frame, 42, and this member 132 has a depending arm 134, (Figs. 12 and 21) with a straight edge along one side engaged by the outer end of the swinging arm 96. A spring 135, is connected with the member 95 132, and the bracket plate 133, so that when the pressure of the outer end of the swinging arm 96, against the straight edge of the depending arm 134, is released, the member 132 is swung upon its pivot. The cam disk 95 128, has a flange 136, through which the notches 127, engaged by the lever 126, are extended, and the member 132, has a pair of upwardly projecting lugs 138 and 139, which are adapted to straddle the flange 136, and 100 if moved a slight amount in either direction serve to present an obstruction to the flange 136, to prevent operation of the star wheel 64. These lugs are arranged so that when the outer end of the arm 96 is engaged with 105 the spiral thread 75, the straight edge of the arm 134, is engaged thereby and holds the member 132 against the tension of its spring 135, in such a position that the lugs 138—139, are properly positioned to permit the flange 110 136 to move readily therebetween. When, however, the outer end of the arm 96 passes beyond the lower end of the thread 75, and is projected into the groove 76, at the base 115 of the thread, it moves the arm 134, and member 132, against the tension of the spring. Inasmuch as the flange 136, is in two sections interrupted only at the notches 127, the swinging of the member 132, is unable to take place until one of the half sections of the flange 136, moves away from between the lugs 138, 139, whereupon the member 132 is free to rotate, and the tension of the spring 99, thereupon throws the lever 95 and arm 96, to the left (looking at Fig. 125 13) and swings the lug 138 around in the path of the succeeding half section of the flange 136. The arrangement of the abutment 130 of the lever 126, and the lever 95, is also such that as long as the end of the 139

arm 96 is engaged with the thread 75, swinging action of the lever 130 does not take place to engage the end of said lever with the notch 127, but as soon as the end of the lever 96 is projected into the groove 76, the release of the lever 95, permits said lever to engage the abutment 130 and swing the lever 126 into engagement with one of the notches 127, at the same time that the member 132 is rotated to bring the lug 138 thereof into position to obstruct the flange 136.

The member 132 also serves at the time the lever 95 is operated to reset the mechanism to begin a new count, to prevent operation of the counting wheel 64, in the following manner: As the lever 95 is retracted against the tension of its spring 99, the arm 96, is withdrawn and releases the pressure thereof against the depending arm 134, of the member 132, whereupon the member 132, is rotated by the spring 135, to bring the lug 138, into the path of the flange 136, and thereby prevent operation of the counting wheel 64. The rotation of the disk 132, is at this time limited by the engagement of the depending lug 140, with the edge of the bracket 133.

For operating the disks 12 and 17 to carry the coin to operate the counting mechanism and discharge same from the machine, there is a shaft 141, (Fig. 3) journaled in bearings 142, of the bracket 9, and extending out through the side wall of the casing 1. A crank 143, is rotatably secured on the outer end of the shaft, and has a clutch engagement with a sleeve 144, which is pinned on the shaft 141, as at 145, so as to rotate with the shaft and slide lengthwise thereon, and there is a spring 146, interposed between a collar 147, on the shaft, and the sleeve 144, so as to hold the latter in clutch engagement with the crank 143. The clutch spaces have an angular relation so that power is transmitted from the crank 143, to the shaft under normal conditions of operation, but upon an abnormal resistance being offered to the operation of the shaft 141, the clutch is automatically released from engagement with the crank 143. A pinion 148, is secured on the inner end of the shaft 141, and meshes with a bevel gear 149, which is secured on the shaft 10, the meshing thereof being arranged in such a manner as to permit the vertical adjustment hereinbefore described, of the shaft 10 and bevel gear 149, without affecting the operation of the gear 149 by means of the pinion 148.

The operation is as follows:

Preparatory to using the machine the lever 46, is adjusted for the particular denomination of coin to be counted, thereby raising or lowering the plate 12, to afford a space between said plate and the ring 19, of the upper disk or plate to accommodate the particular denomination of coin, and such ad-

justment of the lever 46, also positions the lever or finger 61 to provide the proper space between the outer end of the finger and the star wheel 64, according to the diameter of the particular coin to be counted. The knob 119 is also adjusted to the point on the scale 121, which indicates the number of coins which it is desired to count at a time, or if a larger number than indicated on the scale is required to be counted, the knob 91, is adjusted to change the combined pinion member 83—84, to mesh with the proper gears to count decimal multiples of the numbers indicated on the scale 121. The coins are then supplied to the hopper 4, of the machine, and the handle 143 is rotated, and the disks 12 and 17 are operated thereby in opposite directions. As the coins fall upon the plate 12, they are propelled by centrifugal force to the outer edge of the plate 12, until they engage with the ring 21, and as the finger 57, comes in contact with a coin at the outer edge of the plate 12, the coin is carried thereby with the plate 12, around to the point of engagement with the star wheel 64. The end of the lever 61, holds the coin up against the star wheel 64, so that the latter is operated by the passage of the coin, and the engagement of the finger 57, with the coin forces the latter past the star wheel 64 and advances the star wheel the distance of one tooth, after which the coin continues to move forward and is deflected outwardly from the plate 12, by the curved inner edge of the lever 61, and falls by gravity into the chute 62, which discharges it to the exterior of the machine. The operation of the star wheel 64, rotates the shaft 63, one-tenth of a revolution and advances the register 65 one step, and through the gear connection 76 or 77, the combined pinion member 83—84 and the gear 75, rotates the sleeve 74 an equal amount or one-tenth of the amount, as the case may be, that the shaft 63 is rotated. The outer end of the arm 96, which has been engaged with the thread 75, on the sleeve 74, before operating the machine, by retracting the lever 95, and permitting it to engage the thread at the point determined by the position of the plate 100, is moved downwardly according to the rotation of the sleeve 74, by the passage of the coin. As additional coins are moved past the star wheel 64, the outer end of the lever 96, continues to move downwardly until the last coin of the predetermined number has passed the star wheel 64, when the outer end of the lever 96, will have moved downwardly a sufficient distance to disengage from the lower end of the thread 75. By reason of the tension of the spring 99, the lever 95, and together with it the arm 96, is then projected into the groove 76, thereby shifting the arm 134 of the member 132, to operate the latter to bring the lug 138, in front of the advancing half of the

125

130

flange 136, of the cam wheel on the star wheel 64, and at the same time that the arm 96 is projected forwardly, the lever 95 engages the abutment 130, of the lever 126, and 5 throws the outer end of the latter inwardly so as to engage one of the notches 127, of the cam wheel 128, and further operation of the star wheel 64 is thus arrested. It will be observed that the thread 75, need not be constructed with such a high degree of precision that the arm 96, disengages therefrom at the instant of the passage of the last coin from the particular count, but may reach the point of disengagement any time during the passage of the last five coins, as the engagement of the half section of the flange 136, between the lugs 138 and 139, prevents swinging of the member 132, at only two points in the revolution of the star wheel 64, and these two 20 points are reached when a number of coins which is a multiple of five is passed by the star wheel. The arm 134, therefore, of the member 132, is held thereby so as to prevent projection of the outer end of the arm 96, 25 into the notch or groove 76, and the lever 95, is incapable of operation to engage the abutment 130, and shift the lever 126, until the half section of the flange 136 passes beyond the lugs 138—139, so that the operation of 30 the machine cannot be arrested except at half revolution of the star wheel 64.

To reset the machine to repeat the count, or to begin a new count, the lever 95, is moved to the right, (looking at Fig. 13) and 35 the arm 96, at such time, is lifted by the tension of its spring 97, until it engages one of the angularly arranged edges of the plate 100, and as the lever 95 is released and returns to the normal position under the 40 tension of the spring 99, the outer end of the arm 96, slides down the inclined or angular edge portion of the plate 100, until it comes to rest against the thread 75, at the particular point corresponding to the adjustment of the knob 119. During the re-setting operation the counting mechanism cannot be operated, as the withdrawal of the arm 96, releases the arm 134, of the locking member 132, and permits the lug 139 45 to be swung around by the tension of the spring 135, to a position in the path of a half section of the flange 136, so that the star wheel 64 cannot be operated, and as the arm 96, is returned to engagement with the 50 thread 75, the arm 134 is reengaged and the member 132 swung about to the normal position indicated in Fig. 23, in which operation of the star wheel 64 may take place.

After the coin which is being impelled 55 by the finger 57, is discharged from the surface of the plate 12, the inner end of the lever 54, comes in contact with the roller 73, and thereby depresses the outer end of the lever so as to withdraw the finger 57 60 from above the surface of the plate 12, and

permit passage thereof under the finger 61, which holds the coin up against the star wheel.

While I have shown and described my invention in a preferred form, which is designed to count certain quantities of coins, and coins of certain specified denominations, I am aware that it may be changed or modified to count other numbers of coins and other denominations, and may also be changed and modified in various other respects without departing from the principles of my invention, and I therefore do not purpose limiting the patent granted hereon otherwise than necessitated by the prior art.

I claim as my invention:

1. In a coin counting device, the combination of a disk, a ring through which coins are deposited on the disk and spaced from the latter to afford an annular passageway adapted to receive the coins flatwise therein, means for rotating the disk and ring simultaneously in opposite directions, and counting mechanism adjacent the annular passageway adapted to be actuated by coins in the passageway moving thereby. 90

2. In a coin counting device, the combination of a rotary coin carrier, a member spaced thereabove to afford a passage therebetween to receive coins flatwise therein, a retractable coin pushing finger carried by the rotary coin carrier, coin counting mechanism adapted to be operated by the coin between the carrier and said member, an extracting member projecting between the carrier and said member for directing coins radially from the carrier and for holding the coin up against the counting mechanism in its passage thereby, and means for retracting the said finger as it moves past the said extracting member. 95

3. In a coin counting machine, a revolute coin carrying disk, a coin propelling element projecting through said disk and means for actuating said element during each rotation of said disk, to depress and raise the same. 100

4. In a coin counting machine, the combination with a rotary disk, of a member spaced thereabove to provide a coin passage therebetween, and a coin guiding ring member between said disk and member. 115

5. In a coin counting machine, the combination with the coin actuated star wheel, of mechanism actuated thereby and adjustable for locking said wheel after a predetermined number of coins have been counted and means adjustable for varying the operation of said mechanism for multiplying any such predetermined number of coins. 120

6. In a coin counting machine, the combination with the coin actuated star wheel of a rotary element, means operatively connected with said star wheel for rotating said element, mechanism co-operating with said 130

rotary element for stopping said star wheel after a predetermined number of revolutions and a device for varying the relative ratio of rotation of said wheel and element.

5 7. In a coin counting machine, the combination with the coin actuated star wheel, of mechanism for stopping said wheel after a predetermined number of revolutions, and means for retarding the action of said mechanism to increase the relative number of 10 revolutions of said star wheel.

8. In a coin counting machine, the combination with the coin actuated element, of mechanism for stopping said element after 15 a predetermined number of coins have been counted and means for retarding the action of said mechanism until a multiple of the predetermined number of coins have been counted.

20 9. In a coin counting machine, the combination with the coin actuated star wheel of mechanism driven thereby for stopping said star wheel after a predetermined number of revolutions, and means for locking said 25 star wheel during the resetting of said mechanism.

10. In a coin counting machine, the combination with the coin actuated star wheel and shaft thereof, a worm sleeve loosely 30 mounted on said shaft, mechanism operated by said shaft for rotating said sleeve and mechanism coöperating with said worm sleeve and star wheel for stopping said star wheel after a predetermined number of revolutions thereof.

11. In a coin counting machine, the combination with the coin actuated star wheel, and shaft thereof, of a worm sleeve loosely mounted on said shaft, a device progressively 40 actuated by said worm sleeve, means for adjusting the extent of such progressive action, mechanism for driving said worm sleeve at varying rates of speed, and locking means for said star wheel operable by said 45 device.

12. In a coin counting machine, the combination with the coin counting star wheel, of locking mechanism therefor, adjustable mechanism operable at a predetermined time 50 for operating said locking mechanism, and adjustable means for varying the time of operation of said adjustable mechanism.

13. In a coin counting machine, a rotary coin carrying disk, a ring member spaced

therefrom and adjustable to provide a coin 55 passage, a coin deflecting finger extending in said passage, said finger having a slot, mechanism extending through said slot for simultaneously adjusting said coin carrying disk and finger for coins of different denominations. 60

14. In a coin counting machine, a rotary coin carrying disk, a ring member spaced therefrom to provide a coin passage therebetween, and adjustable rolling elements between said disk and ring responsive to adjustments of said rotary disk to vary the height of said coin passage. 65

15. In a coin counting machine, the combination with the coin actuated star wheel 70 and operating shaft thereof, of means for locking said star wheel after a predetermined number of coins have been counted comprising a worm sleeve loose on said shaft, a second shaft, gearing connecting 75 said shafts and sleeve, a locking device for said star wheel, and a device actuated by said worm sleeve for operating said worm sleeve for operating said locking device after said predetermined number of coins have 80 been counted.

16. In a coin counting machine, the combination with the coin actuated element thereof, of locking mechanism therefor and means for operating said locking mechanism 85 at predetermined times comprising a rotary element, a device adjustable with relation to said rotary element for operating said locking mechanism after a predetermined number of coins have been counted, and variable 90 speed gearing connecting said elements.

17. In a coin counting machine, the combination with the coin actuated element thereof, of locking mechanism therefor, a rotary element, a device coöperating with 95 said rotary element and having a plurality of adjustments for actuating said locking mechanism at a preselected time and gearing having a ten to one ratio connecting said elements for operating said device. 100

In testimony whereof I have hereunto subscribed my name in the presence of two subscribing witnesses.
